UNITED STATES PATENT OFFICE

AMOS E. NORTHUP, OF PLEASANT RIDGE, MICHIGAN, ASSIGNOR TO THE MURRAY CORPORATION OF AMERICA, OF DETROIT, MICHIGAN, A CORPORATION OF DELAWARE

DESIGN FOR AN ENGINE COWLING FOR AUTOMOBILES

Application filed January 18, 1933. Serial No. 46,875. Term of patent 7 years.

To all whom it may concern:

Be it known that I, AMOS E. NORTHUP, a citizen of the United States, a resident at Pleasant Ridge, in the county of Oakland, State of Michigan, have invented a new, original, and ornamental Design for Engine Cowling for Automobiles, of which the following is a specification, reference being had to the accompanying drawings, forming a part thereof, wherein:

Figure 1 is a plan view of a forward portion of an engine cowling embodying my design;

Fig. 2 is a view in front elevation of the engine cowling illustrated in Figure 1;

Fig. 3 is a side elevational view of the engine cowling illustrated in Figs. 1 and 2, and

Fig. 4 is a perspective view of the engine cowling illustrated in Figs. 1, 2 and 3.

The dominant feature of said design resides in the configuration of the grill as shown at the forward end of the cowling.

I claim:

The ornamental design for an engine cowling for automobiles as described and shown.

AMOS E. NORTHUP.
